[57] CLAIM

The ornamental design for a radar detector housing, as shown and described.

DESCRIPTION

FIG. 1 is a perspective view of a radar detector housing illustrating my new design with the broken line showing for illustrative purpose only and forming no part of the claimed design;

FIG. 2 is a top plan view of the design of FIG. 1;

FIG. 3 is a front elevational view of the design of FIG. 1;

FIG. 4 is a right side elevational view of the design of FIG. 1;

FIG. 5 is a left side elevational view of the design of FIG. 1;

FIG. 6 is a rear elevational view of the design of FIG. 1; and,

FIG. 7 is a bottom plan view of the design of FIG. 1.
